BRASSIÈRE

Marc E. Chafft, Jamaica, N. Y., assignor, by mesne assignments, to Maude W. Gass, Evelyn Eisen, Elvira C. McKeefrey, and Agnes M. Schoebel.

Application April 19, 1947, Serial No. 742,660

3 Claims. (Cl. 2—42)

1

This invention relates to a brassière and more particularly to a brassière of the strap maintained type having a wire frame incorporated in said brassière.

Brassières of the strap type usually have two sets of straps designed to hold the brassière in such a position on the body of a woman that the two breasts are supported in the normal separated position. One set of straps is attached to the sides of the cup-shaped portion of the brassière and encircle the body of the wearer, passing under the armpits and are fastened at the back. The other set of straps are attached at one end to the tops of the cup-shaped portion of the brassière while the other end is attached to the body encircling strap, and are designed to pass over the shoulders to give the breasts needed support by lifting the cup-shaped portions of the brassière.

This type of brassière defeats the purpose for which it was designed in that it neither separates nor uplifts the bust. Many female difficulties of the breasts are very often attributable to such brassières.

In order to prevent the breasts, particularly the pendant type of female breast, from slipping out of the cup-shaped area of the brassière, the wearer usually tightens the aforesaid straps to such an extent, that the breasts are forced together instead of being separated in the normal position and the tissues of the breast are compressed back against the sternum and ribs of the chest. This compressed condition causes eventual injury to the breast tissues with the attendant malformations which result therefrom.

In addition to the above-mentioned disadvantages, the weight and strain of suspension from the shoulder straps causes them to press uncomfortably on the top of the shoulders leaving unsightly strap depressions on the skin of the shoulders which are particularly noticeable during the summer season when bathing suits or other revealing play suits are worn. Such a shoulder strap, in connection with the usual type of strap brassière, causes an unbalanced uplift of the breast due to the fact that the greatest uplift of the cup-shaped area is provided at the point where the shoulder strap is attached to said cup-shaped area. The rest of the cup-shaped area provides a smaller amount of lift in proportion to the distance it is from the point where the shoulder strap is attached to the cup-shaped area.

Where wires have been built into the brassières, said wires simply supplied a more rigid

2

support than the usual stitched cloth support but did not consider the contour of the breast itself which therefore received support in a limited manner only.

5 It is therefore the main object of this invention to provide a brassière of the strap type having a wire frame which supports the tissues of the female breast on top, sides and bottom to give said breast full bust uplift.

10 Another object of this invention is to provide a wired brassière of the strap type which prevents slipping of the cup-shaped area away from the breast no matter what the movements of the wearer may be.

15 Still another object of this invention is to provide a wired brassière of the strap type which will balance the elevation and the entire weight of the breasts and thereby reduce almost completely the weight and strain of suspension from the shoulder straps.

20 Another object of this invention is to provide a wired brassière of the strap type which will maintain complete separation of the breasts in their normal position yet not apply undue pressure on any part of the breast because of the pull of the body encircling strap or the shoulder strap.

25 Another object of this invention is to provide a brassière of the strap type which incorporates a preformed wire form having a series of compound curves which conforms with the outline of the female breast.

30 Other objects and advantages will appear from the following description considered in connection with the accompanying drawings, in which:

35 Fig. 1 is a front elevational view of the brassière, partially in section.

Fig. 2 is a plan view of the wire support bent in one set of curves.

40 Fig. 3 is a side elevational view of Fig. 2 showing the curves of the wire support.

Fig. 4 is a plan view of another embodiment of the wire support showing the compound curves.

45 Fig. 5 is a side elevational view of Fig. 4 showing the extent of the compound curves of the wire support.

50 Referring now to the drawings and in particular to the brassière shown in Fig. 1, this brassière comprises two cup-shaped bust sections 1 and 2 of any suitable cloth material and approximately three-quarters of a circle in outline. Each bust section 1 and 2 is given the conventional cup-shape by means of darts 3 of different sizes

arranged so as to provide the proper curve outline for the cup-shaped bust sections 1 and 2.

The peripheral edges of each bust section 1 and 2 are formed into tubular selvage edges 4 in any suitable manner, for instance, by turning inwardly the edges of the material and securing such turned in edges to the fabric by stitching.

From each of the outermost medial edges 4 of each bust section 1 and 2, extends a strap 5 comprising a non-elastic fabric section 6 and an elastic section 7 to which is attached a piece of non-elastic fabric 8 having any conventional fastening means, for example, hooks 9 and eyes 10 for securing the brassière in place about the body of the wearer.

Threaded through the peripheral selvage tubing 4 of each bust section 1 and 2 is a relatively stiff but flexible wire element 11 comprised of a single length of preferably stainless steel wire formed at its medial point into an inverted V-shaped open loop 12, the apex 13 of said V being flattened rather than pointed with the rest of the wire element 11 extending on each side of said inverted V-shaped open loop 12 to form an approximately three-quarter loop 14 and 15, terminating in hook-eyes 16 and 17, respectively. The open spaces 18 and 19 resulting therefrom between said hook-eyes 16 and 17 and the flat-topped apex 13 of the inverted V-shaped portion 12 of the wire element 11 is closed by a fabric binding 20, heavily stitched to give it body and maintain its position against the pull of the circularly flexed wire element 11.

Conventional shoulder straps 21 and 22 are stitched at one end to the fabric material section 6 of the body encircling straps 5 while the other end is attached to the edge of the selvage tubing 5 at a point 23 near the hook-eyes 16 and 17 of said wire element 11. Said hook-eyes 16 and 17 are held in position near the end of said shoulder straps 21 and 22 respectively, by means of thread 24 which is sewn through said hook-eyes 16 and 17 to the selvage tubing 5 where it meets the end of the fabric binding 20. A supporting ring 25 inserted in the shoulder straps 21 and 22 enables said shoulder straps 21 and 22 to be adjusted by means of an adjustable member 26 incorporated in each shoulder strap 21 and 22. A pad 27 of plush or other soft suitable material encases the exposed section 28 of the flat-topped apex 13 of the inverted V-shaped portion 12 of the wire element 11 which extends between the separated opposing edges 4 of the cup-shaped fabric sections 1 and 2.

Referring now to the drawings of Figs. 2, 3, 4 and 5, the brassière wire element 11 comprises a pre-formed single wire consisting of a series of compound curves 29, 30 and 31, as shown in Figs. 2 and 3 while another embodiment having a series of compound curves 32, 33 and 34 is shown in Figs. 4 and 5. Due to the shaping of the wire element in the series of compound curves 29, 30, 31, 32, 33 and 34, as described above, the entire bust is supported within the aforementioned cup-shaped sections 1 and 2 of the brassière in such a manner that uplift and separation is given to the breasts of the wearer without causing undue pressure on any part thereof or permitting slippage of the cup-shaped sections 1 and 2 away from the body contour of the breasts.

As will be seen from the above description, the invention discloses a brassière of the strap type having a wire frame preformed into a series of compound curves which conform to the

body contours of the female breasts and thus provide natural separation of the breasts while supplying the necessary up-lift independent of the adjustment of the shoulder straps of the aforementioned brassière.

In addition, said compound curves of said wire frame prevent slippage of the breasts from the cup-shaped cloth area of said brassière by the intimate contact with the profile of the tissues of said breasts and also provides a means of balancing the elevation of the breasts in such a manner that the weight and strain of suspension of the breasts from the shoulder straps are greatly reduced.

15 The spring action of the body-shaped compound curves of the wire insert of my novel brassière, which can best be appreciated by placing the single wire upon a flat plane to demonstrate the nature, disposition, and extent 20 of the curves thereof, produces a firm locking in of the busts within the confines of such curves, the wire locking across the outer pectoral muscles. This effect is produced by the confinement of the bust within the cup of the wire frame, with the compound curves of the frame bearing down around the breast outlines and providing a restraining action against any movement, out of position, of the wire frame. The frame, through its compound curves, is thus 25 shaped to exact conformance with the details of the body contour about the busts.

While, in disclosing the principles of my invention and its preferred embodiment, I have described various detailed structure and relationship, it will be understood that such embodiment and details are given by way of example only and not as limiting the scope of my invention.

I claim:

1. A brassière comprising two breast-supporting fabric sections having outer peripheral edges formed in selvage tubing, a single length of a substantially stiff preformed wire element partially encompassing each of said breast sections, said wire element consisting of two bust encircling parts comprising approximately 270° of a circle joined together at the inner edge of each by a short horizontal element to form a flattened inverted V-shaped portion at the center, and terminating at the outer end in 45 closed loop portions, said wire element also having a series of curves relative to a vertical plane so that the various segments of the wire lie in different horizontal planes to conform to the chest structure, whereby it is adapted in its 50 total configuration to follow the body contour of the female bust in a three-dimensional curve.

2. A brassière as claimed in claim 1, wherein the series of curves relative to the vertical plane, taking as a reference plane a vertical plane passing through the horizontal element, and starting at one end of the horizontal element and progressing around the bust encircling parts, comprises a segment of approximate 50 degrees within the plane, another segment of approximately 65 100 degrees curved toward the wearer, away from the reference plane, another segment of approximately 70 degrees curved away from the wearer, toward the designated plane, and another straight segment of approximately 50 degrees directed from the end of said last mentioned segment toward the designated plane, away from the wearer, and terminating in said looped portions lying within the designated plane.

3. A brassière as claimed in claim 1, wherein

the series of curves relative to the vertical plane, taking as a reference plane a vertical plane passing through the horizontal element and starting at one end of the horizontal element and progressing around the bust encircling parts, comprises a segment of approximately 100 degrees curved toward the body of the wearer, away from the reference plane, another segment of approximately 70 degrees curved away from the body of the wearer, toward the reference plane, another segment of approximately 80 degrees curved toward the body of the wearer, away from the reference plane, and another segment of approximately 20 degrees curving away from the body of the wearer, toward the reference plane and terminating in the looped portion away from the reference plane a small distance toward the body of the wearer.
